UNITED STATES PATENT OFFICE.

ANDREW DISTLER, OF PEORIA, ILLINOIS.

CALK.

No. 869,962.

Specification of Letters Patent.

Patented Nov. 5, 1907

Application filed January 14, 1907. Serial No. 352,179.

To all whom it may concern:

Be it known that I, ANDREW DISTLER, a citizen of the United States, residing at Peoria, in the county of Peoria and State of Illinois, have invented certain new and useful Improvements in Calks; and I do hereby declare that the following is a full, clear, and exact description of the invention, which will enable others skilled in the art to which it appertains to make and use the same.

10 This invention relates to a removable calk for attachment to horseshoes being adapted as a device for preventing slipping of horses on icy surfaces.

An object of my invention is to provide a simple device that can be readily attached to or removed from 15 the horseshoe and by which horses can be "sharp shod" in a very few moments.

A further object is to provide a device of this kind that can be readily attached or removed by an inexperienced person.

20 A further object is to provide a device which can be attached in a moment or two and when worn can be replaced easily and quickly by another at a very low cost.

The invention relates also to certain details of construction as will be pointed out in the specification and accompanying claims.

In the drawing herewith presented, Figure 1 is a vertical section of a horse shoe showing the device attached thereto. Fig. 2 is a perspective view of the device as 30 formed ready for attachment to the shoe. Fig. 3 is also a perspective view of the device showing its form after being placed upon the shoe ready for use.

A indicates the shoe having the usual rear calks B, but one of which is shown, and the toe calk C. So far 35 as the shoe is concerned there is no change in the form over the ordinary ones in common use.

It is my purpose to produce an attachment which can be secured in place without in any way changing the form or conditions of the shoe, and, further, that such 40 attachment can be readily put in position and secured by no other means than its own integral portions.

To the end that my device may be clearly understood I have shown in Figs. 2 and 3 the manner in which it is formed, showing also the slight change in its form 45 after being placed upon the shoe. The device is indicated by the reference letter D and consists essentially of a horizontal U-shaped portion the upper-limb E of which is designed to be slipped over the top of the shoe beneath the hoof while the vertical portion F and the 50 lower horizontal portion G lie respectively at the back of and beneath the toe part of the shoe. The latter portion G extends forward and is then bent downward to inclose the rear side of the toe calk C. An enlargement is formed with the device at H beneath said calk 55 and from thence the metal extends upward at J forward

of the calk C as shown, and terminates in two extensions K K which are bent against the hoof.

As formed ready to be placed upon the shoe the device appears as in Fig. 2 as before described. It is seen that the part J and the extensions K are substantially parallel to the horizontal part G but extend forward at the bottom of the calk as shown in broken lines at a in Fig. 1. This permits the U-shaped portion E F G to be slipped upon the shoe without interference and after being properly placed the part J and its extensions K K are hammered up into the position shown in Figs. 1 and 3 against the calk C and the hoof. The enlargement at H is pointed, as shown, to prevent slipping and may be formed integral with the balance of the device or welded thereto as may be desired. 60 Made of steel the parts can be readily bent to position as described and when the enlargement H is worn away after long use the part J and extensions K K are bent away from the hoof and downward and the device is as readily removed as it was attached after which another can be put in its place. The work of removing an old one and inserting a new one consumes but a few minutes and an inexperienced person can readily attach his own set of calks so that he can always keep his 65 animal "sharp shod."

80 The advantage of my form of calk over those of which I am cognizant is that no fastening means of any kind are used or needed the arrangement being only dependent upon its own peculiar form for holding it firmly in position assisted by the shoe and its toe-calk. As constructed the device presents, when placed upon the shoe, a socket which is designed to receive the toe-calk as shown, the latter preventing movement of said device no matter how much strain may be put upon it 85 assisted, of course, by the upturned extension K K 90 and the part E that locks on the shoe. My device is exceedingly simple and is of low cost while being thoroughly efficient.

As a matter of fact I do not intend to confine myself to having the two extensions K K since one could be 95 used to answer the same purpose, but two of them can be made to more readily fit close against the hoof. However, these extensions may be left off and the upward extension could terminate at or near the top edge of the shoe as shown by broken lines at a since the toe 100 calk would prevent movement of the device.

My device is designed for a shoe having the usual calks and designed to be attached without the necessity of having to remove such shoe from the horse's hoof, being of peculiar form in order to inclose the calk. 105 In addition to this advantage the calk on the shoe assists in preventing movement of the device after being attached by being bent around it. The various strains imposed on the device are met by inclosing the calk by which it is therefore braced. Added to this is the fact 110

that the device is made of one stamping or forging ready to be applied without need of parts such as screws or other secondary devices. The calk H can be readily sharpened or drawn out with a hammer after being heated, or, as before stated, the entire device can be replaced by another without the use of any tools other than a hammer or other similar implement to manipulate the extensions K.

To my knowledge I am the first to apply a detachable one piece calk to a horse-shoe for use in icy weather without first having to remove the shoe or to employ a form to which the calk can be applied. An object of the device is to provide a device that does not require a special shoe or some auxiliary member for holding it in place.

Having thus described my invention, I claim,

1. A detachable calk of the character described, comprising a member having an extremity adapted to enter between the hoof and the shoe, thence extending downward behind the toe portion of said shoe, thence extending forward beneath the shoe, thence extending downward behind the toe calk, thence beneath it, thence forward and upward to inclose said toe-calk and the toe of the shoe and terminating in an upward extension adapted to lie against the hoof, substantially as described.
2. As an article of manufacture, a member having a portion extending rearward then downward, then forward and again downward and provided with an enlargement at the last-named downward portion, and having an upturned portion above the said enlargement, substantially as described and shown.
3. An article of manufacture having a horizontal portion extending rearward, thence downward, then forward

to form a hook, thence extending downward and having an enlargement at and below the downward bent portion, and a horizontal forward projection, substantially as shown and for the purposes set forth. 35

4. A detachable calk comprising a horizontal portion, a vertical downturned portion and a horizontal portion parallel to and beneath the first, arranged to form an enclosure to engage the toe of a horse-shoe in the manner described, and having a downturned portion provided with an enlargement beneath the calk of the shoe, and an extension projecting from such an enlargement adapted to be turned up against said calk and the shoe and against the hoof, substantially as described and shown. 40

5. In a detachable calk, a hooked portion adapted to slidably engage the toe of a horse-shoe in the manner described, and having a downturned portion beneath the toe-calk of the shoe to inclose the same, an enlargement on said downturned portion, and a projection thereon adapted to be turned up against the said toe-calk and the toe of the shoe and against the hoof. 50

6. In combination with a horse-shoe, a detachable calk having a hooked portion to slidably engage the toe of the shoe and adapted to be placed thereon without removal of the shoe from the hoof, and having a portion below the shoe adapted to fit snugly around the toe-calk of the shoe, and a portion forming a part of the device and lying beneath the toe-calk for the purposes set forth, and a second portion extending upward from the first said portion adapted to lie against the shoe and its toe-calk and against the hoof. 60

In testimony whereof I affix my signature, in presence of two witnesses.

ANDREW DISTLER.
